UNITED STATES PATENT OFFICE.

JOHN M. GWINNELL, OF NEWARK, NEW JERSEY.

DESIGN FOR HARNESS-MOUNTING.

SPECIFICATION forming part of Design No. 16,007, dated March 31, 1885.

Application filed January 21, 1885. Term of patent 7 years.

To all whom it may concern:

Be it known that I, JOHN M. GWINNELL, a citizen of the United States, residing at Newark, in the county of Essex and State of New Jersey, have invented and produced a new and original Design for Harness-Mountings; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

In said drawings, Figure 1 is a side elevation of a bolt-hood and sections thereof, taken, respectively, through lines *x* and *x'*. Fig. 2 is a plan of said hook. Fig. 3 is a side elevation of a post-hook and a section of an arm thereof, taken through line *y*. Fig. 4 is an elevation of a terret and a section, taken through *z*. Fig. 5 is an edge view of said terret slightly modified in shape, and Fig. 6 is a sectional view taken through line *z'*.

The leading feature of the design consists in a harness-mounting having an arm or extension thereof sharply bent, as shown, with the portions at each side of the bend concaved, one of the concaved portions being "strap" shaped and the other wire-shaped.

In said drawings, *a* is an arm or extension of the mounting, sharply bent at *b*, as viewed from the side or face, as in Figs. 1, 3, and 4. At each side of the bend in the arm or extension the latter is concavely curved in its outer outlines, as shown at *c c'*, the arm being approximately round, or, as denominated in the trade, "wire" shaped in cross-section, as at *c'*, on one side of the bend, and on the other side flattened or strap-shaped, as at *c*. The outer face-line, *c''*, of the flattened portion in

section is straight, and the inner line is curved, as at *c'''*. At one end of the wire-shaped portion the arm is bulb-shaped or globular, as at *d*. The margins of the strap-shaped portions may project slightly, as illustrated in Figs. 5 and 6, the center being, in consequence, slightly depressed.

Although I show in the drawings but the more important pieces in a set of harness-mountings, the same design may be embodied in other pieces, such as in fly-terrets and hooks; and I do not wish to be understood as donating to the public my design embodying such parts.

What I claim as new is—

1. The design for a harness-mounting herein set forth, the same consisting of a harness-mounting having therein an arm or extension, *a*, sharply bent, as at *b*, concaved, as at *c c'*, at both sides of the projection formed by the bend, one of said concaved portions being strap-shaped and the other wire-shaped, as shown and described.

2. The design for a harness-mounting herein set forth, the same consisting in a harness-mounting having therein an arm or extension, *a*, sharply bent at *b*, concaved at each side of the projection formed by the bend, one of the concaved portions being approximately round or wire-shaped and the other flat or strap-shaped, the inner face of said strap-shaped portion being curved, as at *c'''*, and the outer face flat, as at *c''*, as set forth.

In testimony that I claim the foregoing I have hereunto set my hand this 17th day of January, 1885.

JOHN M. GWINNELL.

Witnesses:

GEORGE SIMONSON,
E. M. REEVE.
